JOHN MURRAY, OF CHOBHAM, ENGLAND

BOOKBINDER'S PRESS

Application filed July 1, 1929, Serial No. 375,310, and in Great Britain September 14, 1928.

This invention relates to a bookbinder's press having relatively movable head and platen elements, and more particularly to presses of the kind described in the prior specification No. 1,527,902 issued 24th February, 1925. The invention has for an object to provide an electrically actuated bookbinder's press of this kind.

The press described in the prior specification includes a fixed head and a movable platen with alternative means for advancing the platen rapidly or slowly. In operation, the material to be pressed is placed in position in the press and partially compressed by advancing the platen rapidly by thrust on a handle carried thereby. The thrust on the material causes a face plate yieldingly supported from the fixed head to retire into contact with the fixed head and thus effect engagement of slow advancing gearing by actuation of which the material may be fully compressed. When the material has been tied up, the slow advancing gearing is disengaged and the platen retracted to permit removal of the material.

In accordance with the present invention, there is provided for moving by power the movable element (say the platen element) an electric motor operatively connected to the gearing and adapted to be rendered inoperative in the cycle of operations of the press.

In practice the gearing is driven by means of a band, chain or the like from an electric motor mounted on a wheeled carriage supporting the press, the current supply connections to which motor are automatically completed and interrupted in the cycle of operations.

In one embodiment of the invention there are carried on the underside of the press table but insulated therefrom a pair of bus bars extending longitudinally of the press, said bus bars being included in the motor circuit, and normally bridged by a brush carried by the movable platen. Attached to the face plate on the fixed head of the press is a contact which, when the face plate is depressed, and after driving engagement of the gearing has been effected, electrically interconnects two stationary contact pillars

included in the motor circuit whereby to start the motor to propel the platen slowly to effect compression of the material.

As in the prior construction, the platen may be rapidly advanced by operation of a handle mounted thereon so that the material is partially compressed to depress the face plate on the fixed head to effect engagement of the gearing and closure of the motor circuit.

When the pressure on the material attains a predetermined intensity, a face plate resiliently mounted on the platen yields to the pressure and in moving releases a trip device carried by the platen so as to effect disengagement of the brush from the bus bars, the motor circuit being thus interrupted and the motor stopped. The timing of the operation of the trip device is regulatable by adjustment of a set-screw carried by the face plate on the platen and co-operating with the trip device. When the material has been tied up, a release lever is operated to disengage the gearing, whereupon expansion of the material moves the platen rearwardly. The face plate on the fixed head is thus relieved and the contact carried thereby is disengaged from the stationary contact pillars. Further rearward movement of the platen brings a follower on the trip device into engagement with a cam whereby the brush is restored to position in engagement with the bus bars.

A bookbinder's press constructed in accordance with the invention is illustrated in the accompanying drawings in which Fig. 1 is a perspective view from the rear side of the press; Fig. 2 is fragmentary longitudinal section; Fig. 3 a fragmentary inverted plan view of the press table. Fig. 4 is a fragmentary detail view showing diagrammatically the means for engaging the planetary gearing.

The press shown includes a fixed head 1 and a movable platen 2 mounted to perform rectilinear movements toward or away from the fixed head 1 on a table 3. 4 denotes a rack bar carried by the platen 2 and meshing with a gear pinion 5. 6 (Fig. 1) denotes a handle carried by the platen 2.

7 denotes a face plate resiliently supported from the fixed head 1. As in the construction described in the prior specification, the face plate 7 is operatively connected to a 5 tappet rod 8 (Fig. 1) serving to trip into operation sun-and-planetary gearing enclosed in a casing 9 so that, when the face plate 7 is urged towards the head 1, said gearing is operatively connected to the gear pinion 5; the drive through said gearing constituting a slow motion drive for the platen 2. 10 denotes a hand lever operatively connected to the tappet rod 8 and adapted to be rocked to effect disengagement of the 15 pinion 5 from the sun-and-planetary gearing, whereby to free the platen 2.

As shown in Fig. 1, the table 3 is supported on pedestals 11 bolted to the table 12 of a wheeled carriage provided with a draw-bar 13. Depending from the underside of the table 12 is an electric motor 14 of which the armature shaft is operatively connected to the sun-and-planetary gearing by means of a chain or band 15 enclosed in a guard casing 16 (Fig. 1). Carried by but insulated from the face plate 7 is a contact fork 17 co-operating with fixed contact pillars 18, 19 of which the pillar 18 is electrically connected to one end of a bus bar 20 extending longitudinally of the press and of which the other pillar 19 is electrically connected to one pole of the motor 14 of which the other pole is electrically connected through a switch 21 to one end of a bus bar 22 disposed parallel with the bus bar 20 but spaced therefrom. 23, 24 denote supply leads to the switch 21. Carried by the platen 2 is a face plate 25 between which and the platen is interposed a plate 26 spaced from the platen 2 by springs 27, the face plate 25 being spaced from the plate 26 by springs 28. Springs 28' are interposed directly between the face plate 25 and the platen 2, said springs penetrating apertures in the plate 26 and serving, in the operation of the press, to transmit the major portion of the load on the face plate 25 to the platen 2. Screw-threaded through the face plate 25, near the lower edge thereof, is a set-screw 29 engageable with the depending arm 30 of a bell-crank lever pivoted at 31 to the platen 2 and having another arm 32 urged downwardly by a spring 33. The arm 32 constitutes a latch normally engaging a spring-urged arm 34 secured to a shaft 35 journalled in brackets 36 depending from the platen. Carried on one end of the shaft 35 is an arm 37 of insulating material to the free end of which is attached a brush 38 normally engaging the bus bars 20, 22 so as electrically to interconnect said bus bars, said brush in conjunction with the arm 37 constituting a switch device. Secured near the other end of the shaft 35 is a lever 39 carrying a follower roller 40 engageable in

the rearward travel of the platen with a stationary cam 41.

In operation, the material to be pressed is placed on the table 3 against the face plate 7. The platen 2 is rapidly advanced by thrust on the handle 6 whereby to compress the material between the face plates 7 and 25. As the face plate 7 retires, the tappet rod 8 is actuated, whereby the sun-and-planetary gearing is operatively connected to the gear pinion 5 and, as the face plate 7 further retires, the contact 17 interconnects the contact pillars 18, 19 whereby the motor circuit is closed and the motor is brought into action to advance the platen further to compress the material. As the pressure increases, the plates 25, 26 on the platen are pressed together in opposition to the action of the springs 27, 28, 28' until, at a point when the requisite pressure has been attained as determined by the setting of the set-screw 29, said screw 29 trips the bell-crank lever 30, 32 and releases the arm 34 whereby the brush 38 moves clear of the bus bars 20, 22 and interrupts the motor circuit to arrest the motor. When the material has been tied up, the lever 10 is manipulated to disconnect the sun-and-planetary gearing from the pinion 5 to permit rearward movement of the platen by expansion of the material. The face plate 7 is now restored to initial position and the contact 17 disengaged from the contact pillars 18, 19. On further rearward movement of the platen 2 by operation of the handle 6 the follower roller 40 engages the stationary cam 41, whereby the trip device 30-35 is reset in the position in which the brush 38 engages the bus bars 20, 22, the press being now ready for a subsequent operation.

I claim:—

1. In a bookbinder's press, in combination with a fixed head and a movable platen, an electric motor for imparting advance movement to said platen, current supply connections to said motor, a brush movable with said platen and engageable with said connections, a trip device also movable with said platen and operatively related to said brush, means movable with said platen for actuating said trip device to disengage said brush from said connections, and means for resetting said trip device and said brush in the return movement of said platen.

2. In a bookbinder's press, in combination with a fixed head and a movable platen, a face plate yieldingly supported by said platen, an electric motor for imparting advance movement to said platen, current supply connections to said motor, a brush engageable with said connections, a trip device operatively related to said brush, and means adjustably fitted to said face plate for actuating said trip device to disengage said brush from said connections.

3. In a bookbinder's press, in combination, a fixed head, a platen movable towards said head to impart by a first-stage movement a preliminary pressure to material located between said platen and said head, an electric motor for imparting a second-stage movement to said platen to impart a final pressure to said material, current supply connections to said motor, a brush movable with 10 said platen and engageable with said connections, a trip device operatively related to said brush, pressure-operated means for actuating said trip device to disengage said brush from said connections, and means for 15 resetting said trip device and said brush.

4. In a bookbinder's press, in combination, a fixed head, a platen movable towards said head to impart by a first-stage movement a preliminary pressure to material located between said platen and said head, an electric motor, a train of gearing through which a second-stage movement is imparted to said platen by said motor, current supply connections to said motor, a brush movable with 20 said platen and engageable with said connections, a trip device also movable with said platen, means for actuating said trip device to disengage said brush from said connections on attainment of a predetermined maximum pressure on said material, and means for 25 resetting said trip device and said brush.

5. In a bookbinder's press, in combination, a fixed head, a platen movable towards said head to impart by a first-stage movement a preliminary pressure to material located between said platen and said head, an electric motor, a train of connections through which a second-stage movement is imparted to said platen by said motor, said train including a 30 rack and pinion and slow motion gearing operatively connectible to said pinion, a manually operable tappet rod to effect operative connection of said gearing with said pinion, current supply connections to said motor, a 35 brush movable with said platen and engageable with said connections, means for starting said motor when said gearing is connected to said pinion, a trip device movable with said platen and operatively related to said 40 brush, means for actuating said trip device to disengage said brush from said connections on attainment of a predetermined maximum pressure on said material and means for 45 resetting said trip device and said brush.

50 In testimony whereof I have signed my name to this specification.

JOHN MURRAY.
